UNITED STATES PATENT OFFICE.

NORMAN B. MILLER, OF NEW YORK, N. Y.

PACKING.

Application filed August 25, 1923. Serial No. 659,357.

This invention relates to improvements in packings and particularly to an improvement in a packing designed for use upon piston rods, plungers, pistons, etc.

5 An object of the invention is to provide a packing which may be easily and cheaply manufactured, which will be durable, and which will be more uniformly efficient than packings heretofore used.

10 A further and more detailed object is to provide a packing of such construction that when in use certain integral portions thereof will tend to move, under the pressure of steam or the like, into tighter engagement

15 with the shaft or piston, while other portions will serve to facilitate in a peculiar, though efficient, manner, such movement, the latter parts also serving to facilitate expansion of the packing under the effects of 20 moisture and the like, and further, to provide an integral portion of the packing so disposed as to act as a buffer or cushion so as to increase the efficiency of operation of the above mentioned portions.

25 Other objects and aims of the invention, more or less specific than those referred to above, will be in part obvious and in part pointed out in the course of the following description of the elements, combinations, 30 arrangements of parts and applications of principles, constituting the invention, and the scope of protection contemplated will be indicated in the appended claims.

35 In the accompanying drawings which are to be taken as a part of this specification, and in which I have shown merely a preferred form of embodiment of the invention:-

40 Figure 1 is a transverse sectional view through a stuffing box showing the packing of this invention in position of use therein,

45 Figure 2 is a transverse sectional view, partly in perspective of a section of the packing constructed in accordance with this invention, and

50 Figure 3 is a view similar to that seen in Fig. 2 but illustrating a modification in which the packing is provided with a suitable sleeve or cover.

55 Referring to the drawings for describing in detail the structure which is illustrated therein the reference character L indicates an ordinary stuffing box having a seat or recess 1 therein closed by the usual gland G, said seat or recess serving to accommodate

the packing which is indicated generally by the reference character H.

The shaft or piston rod 2 passes through this stuffing box and the packing H fits closely thereto.

60 It will be understood that the stuffing box shown is intended merely as an illustration of one way of utilizing this packing and that said box is not a part of the present invention.

65 The packing H is made from a strip of material constructed as in Fig. 2, and there may be as many sections or convolutions as 3, 4, and 5 of this strip within the box as may be required to fill the length of the box.

70 The manner of constructing the strip, as seen in Fig. 2, forms the basis of this invention and said strip may be described as comprising an inner body 6 and an outer body 7, said bodies being joined together by 75 suitable resilient cementitious material as indicated at 8.

75 The body 6 may be described in detail as being of laminated construction made up of alternate layers of relatively stiff material 9 such as canvas or the like, and relatively resilient material 10, such as rubber or the like. The material 9 may be either a close woven or a loose woven fabric. It may be either of wire, cotton, asbestos, or 80 other suitable like material, or it may be even sheet metal, perforated or otherwise, while the material 10 may be any composition of rubber or the like though it is preferably of such consistency that it adheres 85 firmly to the material 6 and binds the whole into a single heterogeneous mass.

90 A structure in which the material 9 consists of canvas, and the material 10 consists of rubber vulcanized into and between the 95 layers of canvas, provides a very desirable and efficient result.

95 As is clearly illustrated in the drawings the layers or laminations comprising the body 6 are given an angular disposition and that those lying between the two lines X and Y extend continuously from the lower or friction side 11 of this body to the upper, or cushion engaging side 12 of said body, while those lying outside of said lines X 100 and Y and completing the corner portion of the body 6 are of successively decreasing length outwardly to the corners as 13.

105 It is important to note, in this connection that the cross sectional width of the body 6,

that is the distance between the outer walls or surfaces 14 and 15, will at all times determine the number of intermediate laminæ occurring between the planes of the lines X and Y, whereas the number of corner forming laminæ occurring outside the planes of said lines will be always the same for a given thickness of packing irrespective of the width of the packing.

10 The upper or outer body 7 may be described as being of laminated construction made up of alternated layers of relatively stiff material 16 and relatively resilient material 17, the actual materials adapted for 15 use in these laminations being substantially the same as for the laminations of the inner body and being preferably canvas and rubber as in said inner body.

The outer body however differs from the 20 inner body essentially in that its laminations are arranged parallel with the inner and outer surfaces 11 and 12 of the inner body while the laminations of the inner body are arranged diagonally with respect to said surfaces. By this arrangement the outer body 25 will comprise a cushion beyond the inner body and be effective for exerting a continuous resilient pressure against the inner body.

In use, the packing constructed as described herein is arranged within the stuffing box as seen in Fig. 1, care being taken to so place the packing that the laminæ of the inner body thereof converge inwardly toward the shaft and toward the inner end of 30 the stuffing box. Steam, or other pressure, attempting to pass outwardly through the stuffing box, that is in the direction as indicated by the arrows in Fig. 1, and endeavoring to pass between the packing and the shaft, and supplemented by the gland pressure, will cause the converging laminæ, and particularly the stiff elements, or layers 9 thereof between the lines X and Y to swing or bend downwardly toward the shaft so 35 that they will engage more firmly with the shaft and will consequently press with increasing force against the outer body or cushion 7. The resilient nature of the laminæ 10, and the somewhat resilient nature of the laminæ 40 9, readily permitting all necessary movements of the laminæ with respect to each other.

The corner forming laminæ, outside the lines X and Y due to the fact that they do 45 not extend continuously between the inner and outer surfaces of the body 6 move as independent bodies and thereby greatly facilitate the proper functioning of the intermediate or continuous laminæ. They constitute 50 groups of broken sections of different lengths capable of moving more freely relative to each other, and it will be apparent that in the length of the stuffing box there occurs alternate groups of broken and unbroken laminæ, the former being produced by

the corner forming laminæ and the latter by the intermediate continuous laminæ of the several sections. The groups of broken laminæ will facilitate and cushion the relatively independent movement of the groups 70 of continuous laminæ.

During all of the movements of the groups of broken and unbroken laminæ in the lower body the same will be under the constant resilient pressure of the upper body, and yet 75 it will be seen that the upper body by its resilient nature will operate to accommodate the movements of the groups in the inner body so that said movements will be rendered more pronounced and efficient by reason of the presence of said outer body. The adaptability of the outer body to facilitate and absorb the angular movements of the laminæ of the inner body will at the same 80 time continue to exert its own resilient pressure uniformly against the inner body is an important value inherent in the structure disclosed.

In the modification Fig. 3 the structure is identical with what has already been described except that this modification proposes the addition of the woven or other suitable cover as 18 which is wrapped, woven or otherwise placed about the packing. Where such a cover is used the two bodies 6 85 and 7 may or may not be cemented together, the cover in this instance being usually sufficient to hold the two bodies in proper assembly.

It should be mentioned that in any instance the tightening up of the gland G will result in relatively greater pressure of the continuous laminæ of the inner body against the upper or outer body than of the broken laminæ of the inner body, and that on this account the line extending through the box separating the inner and outer bodies of the several sections will assume a wavy appearance, the relatively raised portions being in the regions of the respective groups of continuous laminæ, and the relatively depressed portions being in the regions of the intermediate groups of broken laminæ. The outer bodies or cushions while accommodating and absorbing this movement of the several parts 100 of the inner bodies will continue its function of exerting a substantially uniform pressure against the inner body throughout the length of the box.

As many changes could be made in this 105 construction without departing from the scope of the invention as defined in the following claims, it is intended that all matter contained in the above description or shown in the accompanying drawings, shall be interpreted as illustrative and not in a limiting sense.

Having thus described my invention, what I claim as new and desire to secure by Letters Patent is:—

1. A packing adapted to be placed within a stuffing box encircling a shaft in the usual manner, said packing consisting of an elongated body presenting in cross section when within the stuffing box an inner part disposed so as to engage directly against the shaft and an outer part radially beyond the inner part to engage directly against the annular wall of the stuffing box, said two parts being connected together as an integral mass, the inner part extending the full width of the body and being made up throughout of alternate layers of relatively stiff and relatively resilient material, said layers extending obliquely through said inner part, and the outer part also extending the full width of the body and being of a substantially uniformly resilient character throughout its width adapted to serve as a cushion for the inner part substantially as described.
2. A packing adapted to be placed within a stuffing box encircling a shaft in the usual manner, said packing consisting of an elongated rectangular body presenting in cross section when within the stuffing box an inner part disposed so as to engage directly against the shaft and an outer part radially beyond the inner part to engage directly against the annular wall of the stuffing box, said two parts being connected together as an integral mass, the inner part extending the full width of the body and being made up throughout of alternate layers of relatively stiff and relatively resilient material, said layers extending obliquely through said inner part, and said outer part comprising similar alternate layers extending parallel to the inner and outer faces of the packing said outer part also extending the full width of the body and being of a substantially uniformly resilient character throughout its width adapting it to serve as a cushion for the inner part substantially as set forth.
3. A packing adapted to be placed within a stuffing box and encircling a shaft in the usual manner, said packing consisting of an elongated rectangular body presenting in cross section when within the stuffing box an inner part disposed so as to engage directly against the shaft and an outer part radially beyond the inner part to engage directly against the annular wall of the stuffing box, said two parts being connected together as an integral mass, the inner part extending the full width of the body and being made up throughout of alternate layers of relatively stiff and relatively resilient material, said layers extending obliquely through said inner part, and the outer part also extending the full width of the body and being of a substantially uniformly resilient character throughout its width adapted to serve as a cushion for the inner part substantially as set forth.
4. A packing made up in strip form and adapted to be placed in a stuffing box in position encircling a shaft in the usual manner so that a plurality of layers or sections of the strip lie side by side along the length of the stuffing box, and said strip being of a construction such that the several layers thereof along the length of the stuffing box present in cross section alternate groups of broken and unbroken laminae disposed to extend obliquely outwardly from the shaft and a series of cushions one for each group of unbroken laminae, the groups of unbroken laminae being disposed to directly engage the shaft, the cushions being disposed radially beyond the groups of broken and unbroken laminae and directly engaging the annular wall of the stuffing box, and said cushions consisting of alternate layers of relatively stiff and relatively resilient material all of which are arranged normally parallel with the outer wall of the stuffing box throughout the length of the stuffing box.

In testimony whereof I affix my signature.

NORMAN B. MILLER.
